AMPHIBIOUS SURFBOAT

Myron Emmett Howe, Portland, Oreg.

Application March 21, 1935, Serial No. 12,249

3 Claims. (Cl. 115—1)

My invention is comprised primarily of a central hull having any suitable power plant disposed therein. Power is delivered from the prime mover to a pair of supporting driving wheels that are disposed at the front end of the hull when the boat is being used as a land craft. Power for driving the boat as a water craft is delivered to screw propellers mounted upon shafts that are disposed longitudinally of and adjacent the bottom of the hull. The screw propellers are arranged parallel with each other and are mounted upon shafts that are placed within tunnels so that the outer edge of the screw propellers do not extend below the normal bottom line of the hull. The hull is of the flat bottom type which enables the craft to navigate broadside in the surf because it will skid ahead of the breakers and keep it from capsizing.

A steering and supporting wheel is removably secured to the stern of the primary hull. When the vehicle is being used as a land craft it is supported between the front wheels arranged at the forward end of the hull and upon the steering wheel disposed at the stern of the hull. All the wheels are removably secured to the primary central hull and the hull is made sufficiently strong and rigid to prevent the sagging of the same when it is mounted upon the respective wheels. The bottom of the central hull is flat.

The primary purpose in making the bottom flat is to give it greater stability when being operated in shore breakers and to also maintain the same in upright position when being run through the surf.

The stabilizing pontoons that are arranged in spaced relation with the central hull may be used as fuel tanks when the craft is to be used on extensive cruises. This added fuel capacity greatly increases the cruising radius of the craft.

An object of my invention is to provide a craft that may be used as a water borne craft in shallow water and to provide one that may carry sufficient fuel to permit extensive cruising.

A further object of my invention consists in so constructing the craft that it may be used with equal facility as a water craft or as a land craft.

And a still further object of my invention consists in so constructing the craft that it may be propelled in the surf and where a propelling efficiency may be secured in the surf waters that are largely filled with air bubbles.

Heretofore in craft used as surf boats, the specific gravity of the water being so light, owing to air bubbles contained therein, but little

efficiency was obtained from the screw propellers ordinarily used. By using my propelling screws in the bottom of the flat boat a larger blade surface is obtained, thus greater efficiency is obtained in the propulsion of the boat. This also permits the propelling of the craft in extremely shallow water even in surf waters adjacent the shore line of the sea to thereby produce a craft that may be successfully used in the saving of life along the shore.

A further object of my invention consists in so constructing the craft that steering facilities are provided even when the craft is being propelled in foamy water in the surf along the shore.

And a still further object of my invention consists in providing a dual steering apparatus to be used either on land or in the water.

With these and incidental objects in view, the invention consists in certain novel features of construction and combination of parts, the essential elements of which are set forth in the appended claims, and a preferred form of embodiment of which is hereinafter shown with reference to the drawings which accompany and form a part of this specification.

In the drawings:

Fig. 1 is a side view of my new and improved craft illustrating the same as being supported upon the wheels disposed at the front and at the stern of the craft and having the side stabilizers in place and position.

Fig. 2 is a plan view of the craft illustrated in Fig. 1.

Fig. 3 is a stern view looking forward of the assembled craft in which a part of the steering wheel assembly is shown in section.

Fig. 4 is a fragmentary sectional plan view of the steering wheel housing and support. This view is taken on line 4—4 of Fig. 3, looking in the direction indicated.

Fig. 5 is a fragmentary perspective end view of the propeller tunnel housing.

Fig. 6 is a fragmentary sectional plan view of the craft showing the front supporting wheels and illustrating the motive drive for the craft. In this view is also shown the connecting drive disposed between the front axle and the propeller shafts disposed at each side and extending longitudinally of the hull.

Fig. 7 is a sectional side view of the propeller tunnel housing and bearing for the propeller shaft, the propeller being shown in full side view. This view is taken on line 7—7 of Fig. 3, looking in the direction indicated.

Fig. 8 is a fragmentary sectional side view of

the outer bearing and hub of the front axle. This view is taken on line 8—8 of Fig. 6, looking in the direction indicated.

Fig. 9 is a fragmentary sectional end view of 5 the hull and an end view partially in section of the stabilizer pontoon that is spaced apart from the hull and illustrates one of the front wheels disposed within the space provided between the stabilizing pontoons and the hull. This view is 10 taken on line 9—9 of Fig. 2, looking in the direction indicated.

Fig. 10 is a front view of the brake control lever assembly and illustrates the same as being secured to a pair of hydraulic or pneumatic cylinders. 15

Fig. 11 is a side view of the brake control lever assembly. This view is taken on line 11—11 of Fig. 10, looking in the direction indicated.

Like reference characters refer to like parts 20 throughout the several views.

My present invention is comprised primarily of a central hull 1. The central hull 1 is comprised of a forward cabin 2 and a cock-pit 3. The cabin 2 is an enclosed cabin having windows 25 4 disposed therein adjacent the top of the cabin. Access is had to the enclosed cabin through any suitable door 5. A relatively large transparent covered opening 6 is disposed in the forward end of the cabin through which the course of the vessel may be observed. The side walls 7 of the central hull are preferably made of a single sheet of any suitable material as metal or plywood. The bottom 8 of the hull has a substantially flat major surface area and has a slightly up-turned bow 9. Stabilizer pontoons 10 and 11 are disposed at each side of the hull and extend for the major portion of the length of the central hull 1. These pontoons are normally spaced apart from the central hull and are secured thereto by suitable brackets and braces. Deck covers 12 and 13 extend from the central hull to the outer surface of each of the pontoons. Relatively large U-shaped rigidly fabricated members 14 are spaced along each side of and secured to the hull 1 and the pontoons 10 and 11 are secured to the U-shaped members. Reinforcing brackets 15 and 15A reinforce the U-shaped members 14.

Suitable fastenings as bolts 17 and 18 extend through the legs of the bracket 15 and secure them to the body of the pontoon and to the side wall of the primary hull 1.

An axle housing 19 is positioned adjacent the bottom of the primary hull and power is delivered to the axle shafts 23 and 24 from a driving shaft 20 that is connected with any suitable prime mover.

Hubs 21 and 22 are secured to the inside of the side walls 7 of the primary hull and stub axles 27 and 28 are disposed through the hubs 60 21 and 22 respectively. Splined sleeves 25 and 26 secure together the stub shafts 27 and 28 and the axles 23 and 24 respectively, and inner hubs 31 and 31A are disposed within the hubs 21 and 22 respectively and the bore of the inner hubs 65 is adapted to intimately engage the tapered ends of the stub axles while the outer periphery of the inner hubs intimately engages with the bores of the hubs 21 and 22. The construction of this assembly is best illustrated in Fig. 8. Pairs of brackets 29 and 30 are secured to the flange of the inner hubs 31 and 31A as by stud bolts 34 and the wheels 32 and 33 are in turn secured to the pairs of brackets 29 and 30 respectively.

When it is found necessary or desirable to 75 remove the supporting wheels 32 and 33 from the

driving shafts the pairs of brackets 29 and 30 are removed from the flange of the inner hubs 31 and 31A by the removal of the studs 34. This permits a removal of the wheel assembly leaving the stub axles substantially flush with the sides 5 of the boat. A cover plate may then be placed thereover and be secured thereto to completely cover the outer end 35 of the respective stub shafts. Water-tight relationship is maintained about the stub shafts 27 and 28 by forming a 10 stuffing box about the respective stub shafts at the hub. This is comprised primarily of a gland nut 36 that is threadedly or otherwise secured to the hub and by the placing of any suitable packing 37 about the respective stub shafts. A 15 fluid tight working relationship is maintained therebetween by the adjusting of the gland nut 36.

Use of the craft solely as a motor boat may be 20 accomplished by removal of the wheels and stabilizing pontoons 10 and 11. Removal of the pontoons is accomplished by the removal of the fastening bolts 17 and 38, illustrated in Fig. 9, that extend through the respective U-shaped brackets 14, to thereby permit the free removal 25 of the stabilizing pontoons from the central hull 1. The plugging of the holes through which the fastening bolts are passed is made after the removal of the stabilizing pontoons. One or more steering wheels 39 may be disposed at the stern 30 of the central hull and are directly secured to a supporting structure that is removably secured to the stern of the central hull 1. The supporting structure is comprised of plate members 41 and 42 that are secured, as by bolts 43, to a plate 35 member 40 which in turn is secured to the stern of the hull 1. A cross member 75, having a cylinder 76 formed integrally therewith and extending upwardly therefrom, is secured between the plate members 41 and 42. A second cross member 77, comprising a pair of spaced plates 78 and 79, is also secured between the plate members 41 and 42. A flange 80 is provided at the top of the cylinder 76 and the cylinder 76 is secured to the cross member 77 by placing bolts 81 through 40 the flange 80 and the plate 78.

The steering wheel 39 is suitably journaled within a bifurcated member 82. A supporting shaft 83 upwardly extends from the bifurcated member 82 and is journaled with bearings 84 and 85 that are disposed within the cylinder 76. A resilient member as a spring 86 is disposed about the shaft 83 and between the bearings 84 and 85. The upper end of the shaft 83 terminates in an elongated square portion 87. The square portion 87 extends through the plates 78 and 79 of the support 77 and also extends through the tiller 88 which is disposed between the plates 78 and 79. This construction enables the spring 86 to act as a shock absorber since the bearing 84 60 is free to move longitudinally of the cylinder 76 and the shaft is free to move through the fixed bearing 85 and the square portion 87 is free to move through the tiller 88 and the plates 78 and 79. A nut 89 placed on the end of the shaft 87 65 prevents disengagement of the steering wheel assembly from its supporting structure.

A pair of pressure cylinders 90 and 91 are secured to the back plate 40A and a piston 92 is disposed within each cylinder. A rod 93 is secured to each of the pistons and a clamp 94 is secured to the rod 93 midway between the pistons 92. The tiller 88 is slidably and rotably secured to the clamp 94.

When it is desired to turn the steering wheel 75

39, fluid pressure is applied to one of the pistons 92 through conduits 95 and 96 leading from any suitable source of supply and control, not here shown, and longitudinal movement is imparted 5 to the rod 93 which in turn imparts a rotary movement to the tiller 88 and wheel 39.

To secure suitable driving and steering for the speed boat when the same is to be operated in particularly shallow water, I provide tunnels 44 and 45 at each side of the underside of the primary hull 1. These tunnels are open at the bottom and at the back end. Shafts 46 and 47 are disposed through hubs 56 that are secured to the end wall of the tunnels 44 and 45 respectively. 10 Shafts 52 and 53 are journaled within suitable bearings and have pinions 48 and 49 respectively disposed upon their one end. These pinions 15 coact with and are driven by bevel gears 50 and 51 respectively that are mounted upon the axle 20 shafts 23 and 24 respectively. A clutch 54 is disposed between the shafts 46 and 52 and a clutch 55 is disposed between the shafts 47 and 53. The shafts 46 and 47 are journaled relative to the tunnel housing by suitable bearings 57 disposed 25 within the hubs 56. Screw propellers 58 and 59 are mounted upon the respective shafts 46 and 47. The diameter of the screw propellers 58 and 59 is such that they will not extend below the flat 30 bottom of the central hull 1. When the central hull 1 has wheels mounted thereupon and the same is to be used as a land vehicle the clutches 52 and 53 are manipulated to thereby prevent the rotation of the screw propellers.

To prevent water entering the hull through the 35 inner hubs 56 gland nuts 60 are secured to the inner end of the hub and a stuffing box is made thereby with suitable packing 61 being disposed about the respective shafts 46 and 47. The tunnel housing may be secured to the hull as by screws 40 or bolts 44A.

While I have shown but one pair of tunnel 45 housings and but one pair of screw propellers disposed upon the underside of the primary hull 1, I do not wish to be limited to a single pair of screw propellers as a plurality of screw propellers might be placed in spaced relation along the shaft to thereby develop the full operating efficiency of the screws. This is fundamentally important in surf boats, as the surf is largely 50 made up of foam which lessens the specific gravity of the medium in which the surf boat is to operate and the propelling efficiency of the single screw is largely ineffective for that reason. Providing a plurality of spaced propellers upon each 55 of the shafts that extend longitudinally of the underside of the craft greatly affects the rapid mobility of the craft when being operated in the surf.

When the wheels are removed and the craft is 60 to be used as a water borne craft the clutches are again actuated and power is then applied to the screws 58 and 59. The under water bearings 57 are made of a suitable material to permit the long and useful life of the same by providing 65 antifriction blocks disposed therein that are properly protected with suitable lubricant holding housings.

The steering of the hull may be accomplished 70 by placing brake drums 62 and 63 upon the respective shafts 23 and 24 and suitable brake bands 64 and 65 are placed within the respective drums 62 and 63. These brake bands and drums may be of the conventional hydraulic or friction 75 type commonly used in automotive vehicle construction.

In Fig. 10 is shown the brake control mechanism. It is comprised of a control handle 64 having a socket 65 disposed at one end. The socket 65 engages a ball 66 that may be supported in any desired manner within the driving compartment of the hull. Arms 67 and 68, having right angle bends, extend from each side of the socket 65 and terminate in sockets 69 and 70 respectively. A pair of hydraulic brake cylinders 71 and 72 is provided, one for each of the brakes 10 62 and 63, shown in Fig. 6, and suitable piping connections are provided to connect the respective cylinders with the brakes. Connecting links 73 and 74, each having a ball on one end to engage within the sockets 69 and 70 respectively and each 15 having a socket disposed at the opposite end to form a ball and socket joint with the piston rod of the hydraulic cylinder.

It will be seen from the foregoing description that as the brake handle 64 is actuated to the left the hydraulic cylinder 72 will cause pressure to be applied to the brake 62. When the brake handle is actuated to the right, the brake 63 will be applied. When the brake handle is actuated toward the operator or in the direction 20 indicated by the arrow in Fig. 11, both brakes 25 62 and 63 will be applied.

When in water, and the clutches 54 and 55 are engaged, and the brakes are applied to one of the propellers, the craft will turn. 30

While the form of mechanism herein shown and described is admirably adapted to fulfill the objects primarily stated, it is to be understood that it is not intended to confine the invention to the embodiment herein shown and described, 35 as it is susceptible of embodiment in various forms, all coming within the scope of the claims which follow.

What I claim is:

1. An amphibious craft comprising a flat 40 bottom hull having sides perpendicular to the bottom; stabilizing pontoons removably secured to the sides of the hull; power transmission means disposed within the hull and adjacent the front; wheels secured to either side of the boat and operatively connected to the transmission means; propeller shafts operatively connected to the transmission means; screw propellers secured to the outer ends of the propeller shafts; clutches disposed in the propeller shaft line; housing members set within the bottom of the boat for 45 housing the propellers; brake mechanisms associated with the axles of the transmission means; means for controlling the brake mechanisms; a steering wheel mounted at the rear of the hull; shock absorbing means disposed within the wheel 50 mounting and hydraulic means associated with the steering wheel for steering the craft. 55

2. In a device of the class described, the combination of a primary flat bottomed hull having sides perpendicular to the bottom, stabilizing pontoons removably secured to the sides of the hull, supporting and propelling wheels removably disposed at opposite sides and adjacent the front end of the hull, a common driving actuator for each of the supporting and propelling wheels, a pair of 60 shafts disposed longitudinally of the primary hull and operatively connected to the driving means, screw propellers disposed upon each of the shafts, an independently operated clutch disposed in each propeller shaft line, hydraulic brake 65 mechanisms associated with the axles of the driving means, and means for individually controlling the brake mechanisms.

3. An amphibious craft comprising a flat bottom hull having sides perpendicular to the bot- 75

tom; stabilizing pontoons removably secured to the sides of the hull and spaced apart therefrom; power transmission means disposed within the hull and adjacent the front; wheels detachably secured to either side of the boat adjacent the front and operatively connected to the transmission means; propeller shafts operatively connected to the transmission means; screw propellers secured to the outer ends of the propeller shafts; clutches disposed in the propeller shaft

lines; housing members set within the bottom of the boat for housing the propellers; brake mechanisms associated with the axles of the transmission means; means for operating the brake mechanisms independently and simultaneously for steering the craft and braking the craft respectively; a trailing wheel mounted at the rear of the hull; and shock absorbing means disposed within the wheel mounting. 5

MYRON EMMETT HOWE. 10
